Primary Examiner — Richard Kearney*Assistant Examiner* — Landon Thomas Cassell(74) Attorney, Agent, or Firm — Fenwick & West LLP(57) CLAIM

The ornamental design for a rejuvenating device, as shown and described.

DESCRIPTION

FIG. 1 is a perspective view of a rejuvenating device. FIG. 2 is a bottom view of a rejuvenating device. FIG. 3 is a top view of a rejuvenating device. FIG. 4 is a right side view of a rejuvenating device. FIG. 5 is a left side view of a rejuvenating device. FIG. 6 is a front view of a rejuvenating device; and, FIG. 7 is a back view of a rejuvenating device. The broken lines in the drawings showing portions of the rejuvenating device are included for the purpose of illustrating environmental structure and form no part of the claimed design.
